MULTI-CONTACT ELECTRICAL CONNECTOR
Charles R. Curtis, Camp Hill, and Lincoln E. Roberts,
Harrisburg, Pa., assignors to AMP Incorporated, Harrisburg, Pa.

Filed Mar. 29, 1962, Ser. No. 183,554
5 Claims. (Cl. 339—49)

This invention relates to multi-contact electrical connector assemblies and particularly to an improved insulating block for such assemblies.

An object of the invention is to provide an improved hermaphroditic connector block. A further object is to provide a connector block which is self-polarizing and which permits keying of the two blocks of a connector assembly in order to prevent mismatching among two or more connector assemblies. A still further object is to provide a hermaphroditic connector block adapted to receive contacts which project from the mating face of the block and which has a hood in surrounding relationship to the projecting contacts.

These and other objects of the invention are achieved in a preferred embodiment comprising a dielectric block formed as a unitary molding and having a mating face onto which the contact receiving cavities open. A plurality of spaced-apart flanges are provided on the sides of the block and in surrounding relationship to the mating face to form a shield or enclosure in protective relationship to the projecting ends of the contacts. Recesses complementary to the flanges are formed on the sides of the block and between adjacent flanges and the flanges and recesses are so spaced that the block is mateable with an identical block and is self-polarizing with respect thereto. In addition to polarization, the preferred embodiment of the invention permits keying of each individual block to its mating counterpart upon removal of one of the flanges on one of the blocks and insertion of a blocking wedge into the corresponding recess of the other of the blocks. With this arrangement, only the blocks so keyed can be assembled to each other since a third block which did not have the appropriate flange removed could not be assembled to the block having a wedge in the appropriate recess.

In the drawing:

FIGURE 1 is a perspective view showing a connector assembly in accordance with the invention.

FIGURE 2 is a top plan view showing a pair of connector blocks spaced apart and in alignment with each other preparatory to their being brought into engagement.

FIGURE 3 is a view similar to FIGURE 2 but showing the blocks in engagement with each other.

FIGURE 4 is a view taken along the lines 4—4 of FIGURE 2; and

FIGURE 5 is a perspective view of a blocking wedge used for keying connector blocks to each other.

A connector assembly in accordance with the invention comprises a pair of blocks 2, 2' which are identical to each other so that a description on one will suffice for both. Accordingly, only the block 2 will be described in detail and the same reference numerals differentiated by prime marks, will be employed to denote corresponding parts of the block 2'.

The block 2 comprises a generally rectangular unitary molding having shoulders 4 on its opposite ends. Jack screws 6 are rotatably mounted in the shoulders for engagement with complementary sockets 6' which are non-rotatably mounted in the block 2' to provide a mechanical advantage if required when the blocks are assembled to each other and to hold them in assembled relationship. A plurality of contact receiving cavities 8 extend through the block 2 from the rearward surface to the

2

mating face 12 which is disposed against the face 12' of the block 2' when the blocks are assembled to each other. Contacts secured to the ends of wires are disposed in the cavities and have projecting end portions which extend beyond the surface of the mating face 12. The contacts are not shown in the drawing in the interest of clarity since the blocks themselves, rather than the contacts, are the subject matter of the instant invention. The generally rectangular cavities of the disclosed blocks are adapted to receive a hermaphroditic type contact as described in the copending application of Lincoln Roberts (Serial No. 183,542), filed March 29, 1962, although any suitable electrical contact can be used in a connector assembly in accordance with the invention.

15 A plurality of flanges 18, 19, and 26 integral with the block 2 extend from the sides of the block and surround the face 12 to form a protective hood or enclosure around the projecting ends of the contacts in the block. Recesses 16, 23 are provided between adjacent flanges 20 and are complementary to the flanges so that the blocks are hermaphroditic, that is, the blocks are identical with each other and will mate with each other. The flanges and recesses are provided with complementary tapers as shown to facilitate the use of a keying wedge described below.

25 The hermaphroditic effect is achieved by virtue of the fact that the flanges are symmetrically arranged about the major axis B—B in the plane of the mating face 12 but are non-symmetrical with respect to the minor axis 30 A—A. Particularly, the flanges and recesses are disposed with respect to this minor axis A—A such that it passes between a flange and recess on both of the sides 22, 23. Thus, the end 14 of the block 2 has a centrally located flange 18 which is diametrically opposed to a 35 recess 16 on the opposite end 15 of the block. The side 22 of the block on the other hand, has flanges 26 which are diametrically opposed to flanges 27 on the opposite side 23, and the side 22 has recesses 28 which are diametrically opposed to recesses on the opposite side 23.

40 The cavities 8 in the blocks are also arranged symmetrically with respect to the axis B—B. In the disclosed embodiment, these cavities are arranged asymmetrically with respect to the axis A—A in order to achieve the hermaphroditic effect. Thus, in the disclosed embodiment, the axis B—B bisects the central column of cavities and two columns are symmetrically arranged on each of its sides. The rows of cavities extending parallel to the axis A—A are asymmetrically arranged, four rows being provided on each side of the 45 axis. These rows may not be disposed randomly but must be arranged such that a cavity on one side of the axis of one block will be brought into registry with a cavity on the opposite side of the axis of a mating block when the two blocks are engaged with each other. As 50 an alternative, the cavities may be arranged symmetrically with respect to both axes if registry is achieved when two identical blocks are brought together.

55 The face of the block must be symmetrical about one axis but need not be symmetrical about the other. For 60 example, the face of the block might be in the form of a trapezoid.

65 Connector blocks in accordance with the invention are self-polarizing since they can not be brought into engagement with each other unless the recess 16 of the block 2 is aligned with the flange 18' of the block 2'. The practice of the invention thus achieves both a polarizing effect and a protective hood or enclosure in surrounding relationship to the projecting contacts without 70 the use of specialized polarizing devices as have been common in the prior art. In addition to polarization, however, it is sometimes necessary to key each half of a

connector assembly to its mating half in order to prevent mismatching where two or more connector assemblies are mounted in close proximity to each other. Where two connector assemblies are so mounted, simple polarization will not prevent careless assembly of a part of one connector assembly with the corresponding part of the other connector assembly. In accordance with the instant invention, keying to prevent such mismatching is achieved by removing any one of the flanges of one of the blocks and inserting a wedge as shown at 32 into the complementary recess of the other one of the blocks. In FIGURE 2, the central one of the flanges 26 has been removed from the side 23' of the block 2' and a wedge 32 has been placed in the opposite recess 23 of the side 22 of the block 2. With this recess blocked by the wedge 32, it is impossible to assemble a block other than the block 2' to the block 2 in FIGURE 2 since the flange which would normally occupy the recess closed by the block 32 can not enter this recess. As mentioned above, the flanges and recesses are tapered in the directions of their lengths to facilitate the use of the wedge. Additionally, the recesses are reentrant at the bottoms of their sides as shown in FIGURE 4. This configuration prevents the wedges from being accidentally removed after insertion.

In order to achieve complete keying of each of a group of connector assemblies, each individual connector assembly should be keyed in the manner shown in FIGURES 2 and 3, that is, one flange should be removed from one connector block of each assembly and a wedge 32 inserted into the complementary recess of the other block of the assembly. Each individual assembly should, of course, be keyed by removal of a flange and blocking of a recess which does not correspond with a removed flange of an adjacent connector assembly. The disclosed embodiment of the invention provides seven removable flanges on each block so that seven different keying arrangements can be achieved with the one form of the block.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

We claim:

1. A multi-contact connector block comprising a generally prismatic unitary molding of insulating material adapted to be engaged with an identical block, said block having a planar mating face movable against the mating face of said identical block, a plurality of cavities extending through said block and opening onto said mating face, spaced-apart flanges on said block in surrounding relationship to said mating face and recesses between said

flanges, said recesses being complementary to said flanges and adapted to receive said flanges, a first pair of opposite sides of said block having a flange on one side diametrically opposed to a recess on the opposite side, and a second

5 pair of opposite sides having flanges diametrically opposed to flanges and recesses diametrically opposed to recesses whereby, said block is matable with and polarized with respect to said identical block, said flanges forming a protective enclosure in surrounding relationship to projecting portions of contacts disposed in said cavities.

2. A multi-contact connector block comprising a generally prismatic unitary molding of insulating material adapted to be engaged with an identical block, said block having a planar mating face movable against the mating face of said identical block, said mating face being symmetrical about at least one axis of its plane, a plurality of contact receiving cavities extending through said block and opening onto said mating face, said cavities being symmetrically arranged with respect to said one axis, 15 spaced-apart flanges on said block in surrounding relationship to said mating face and recesses between flanges, said recesses being complementary to said flanges and adapted to receive said flanges, a first pair of opposite sides of said block having a flange on one side diametrically opposed to a recess on the opposite side, and a second pair of opposite sides having flanges diametrically opposed to recesses whereby, said block is matable with and polarized with respect to said identical block, said flanges forming a protective enclosure in surrounding relationship to projecting portions of contacts disposed in said cavities.

3. A device as set forth in claim 2 wherein one of said flanges has been removed from said block and the corresponding recess of said identical block has been filled 30 whereby said blocks are keyed with respect to each other.

4. A multi-contact connector block comprising a prismatic unitary molding of insulating material adapted to be engaged with an identical block, said block having a planar mating face movable against the mating face of said identical block, said mating face being symmetrical about at least one axis of its plane; a plurality of rows of contact receiving cavities extending through said block and opening onto said mating face, spaced-apart flanges on said block in surrounding relationship to said mating face and recesses between said flanges, said recesses being complementary to and adapted to receive, said flanges, said rows of cavities and said recesses and flanges being symmetrically arranged with respect to said one axis, said flanges forming a protective enclosure in surrounding relationship to projecting portions of contacts disposed in said cavities.

5. A device as set forth in claim 4 wherein one of said flanges has been removed from said block and the corresponding recess of said identical block has been filled 50 whereby said blocks are keyed with respect to each other.
